UNITED STATES PATENT OFFICE.

AL FRYER, OF CHICAGO, ILLINOIS, ASSIGNOR TO WILLIAM GRIMSHAW, OF GLEN ELLYN, ILLINOIS.

ACCELERATOR VALVE FOR SPRINKLER SYSTEMS.

Application filed August 21, 1924. Serial No. 733,277.

This invention relates to valves designed and adapted for accelerating the venting of "dry" automatic sprinkler systems and the tripping and opening of the differential valves which control the admission of water to said systems, commonly known as accelerator valves.

In a "dry" automatic sprinkler system, the pipes of the system contain no water but air under pressure, the admission of water thereto from any suitable source of supply, as directly from a water main or a gravity or pressure tank, being controlled by a differential air and water valve, the air valve of which is sufficiently larger than the water valve, that a relatively low air pressure in the system, acting on the relatively large air valve, will maintain the relatively small water valve closed against the relatively high water pressure on the supply side thereof. A usual differential between the areas of the air and water valves is 5.5 to 1, whereby an air pressure of from 25 to 50 pounds in the sprinkler system will counter-balance a water pressure of from 70 to 100 pounds acting on the water valve, with an adequate margin of safety.

When a sprinkler head of a "dry" system is ruptured from any cause—as by exposure of the fusible member thereof to fire—the pipes of the system will be vented, thus permitting water to enter the system, **in a** familiar manner.

It is found in practice, however, that it frequently requires a considerable interval of time for the system to be fully vented and for the water admitted to the system to reach the ruptured sprinkler head or heads, during which time the fire may spread and gain headway, thus rendering it correspondingly more difficult to extinguish the fire and increasing the fire loss.

To remedy this objectionable feature, it has been proposed to equip such systems with devices commonly known as accelerator valves, designed and adapted for expediting the venting of said systems, so that water will reach a ruptured head in the least possible time.

Prior to my invention, all accelerator valves of which I have any knowledge, have been complicated in construction, correspondingly expensive to manufacture and in most cases unreliable in operation.

The object of the present invention is to provide an accelerator valve for the purpose specified, which will be simple in construction, inexpensive to manufacture and which will be effective and reliable in operation.

To this end, an accelerator valve embodying my invention and improvements comprises the various features, combinations of features and details of construction herein-after described and claimed.

Figure 1 is a central, sectional view of an accelerator valve embodying my invention and improvements.

Figure 2 is a sectional plan view thereof, on the line 2—2 of Fig. 1.

Figure 3 is a central, longitudinal sectional view of the separator unit; and

Figure 4 is a fragmentary sectional plan view on the line 4—4 of Fig. 1.

Describing my invention with particular reference to the drawings, my improved accelerator valve comprises a casing designated as a whole A, comprising separate sections *a*, *a'*, bolted or otherwise rigidly secured together. The interior of the casing A is divided transversely by a flexible diaphragm *a*² into separate compartments 1 and 2 which, for purposes of convenient reference, will herein be designated, respectively, as "first" and "second" compartments. The diaphragm *a*² may be made of any suitable material, preferably sheet rubber, and is secured in position by clamping its edges between the connected faces of the casing sections *a*, *a'*.

The casing A is provided with air admission and discharge openings 3 and 4 which communicate with the compartment 1 formed by the casing section *a*, the admission opening 3 directly, and the discharge opening 4 by means of a hollow elbow or nipple 5 provided with an opening 6 which connects the interior thereof with said compartment 1, said opening being controlled by a valve, designated as a whole A¹, comprising a clapper 7 adapted to engage a valve seat 8 which surrounds the opening 6, and which is connected to and supported by the diaphragm *a*², so as to be movable towards and from said valve seat. As shown, the valve seat 8 is formed on a bushing 9 made of bronze or other non-corrosive metal.

As the accelerator valve is installed for use, the admission and discharge openings 3 and 4 are adapted to have pipe connections,

respectively, with a sprinkler system—usually the opening 3 is connected with a riser of the system directly adjacent to the dry pipe valve—and the opening 4 with the atmospheric chamber of said dry pipe valve, commonly referred to as the intermediate chamber of the valve, defined by the air and water valves thereof, or said opening 4 may lead directly to atmosphere; in the first case accelerating venting of the system and also producing pressure in the intermediate chamber of the dry pipe valve tending to open the air valve, and in the second case, merely accelerating venting of the system.

15 The valve clapper 7 is confined in a recess 10 in the end of the valve case, which maintains it in operative relation to the valve seat 8 and guides it in its movement towards and from the same. For convenience and economy of manufacture, said recess is formed in a plug 11 which has screw-threaded engagement with a hole formed in the end of the valve casing. Said plug, being removable, also affords access to the chamber 1 of the 25 valve casing for assembling the valve A¹, for purposes of inspection, for cleaning the valve seat and for other purposes.

To permit free access of air and water contained in the compartment 1 of the valve casting to the upper end of the valve clapper 7, said clapper is made smaller in diameter than the recess 10, and formed thereon are guide lugs or projections 12 which are fitted, with slight clearance, to said recess.

30 35 The valve clapper 7 is connected to and supported by the diaphragm a², so that flexure of said diaphragm in opposite directions will impart movement to said valve clapper towards and from the valve seat 8 to open or close the valve A¹, as the case may be.

To provide for assembling the parts of the valve A¹ around the elbow 5, the valve clapper 7 forms a separate part and is detachably secured to the upper ends of posts or standards 45 13 secured to a plate 14 attached to the diaphragm a². As shown, said valve clapper has screw-threaded engagement with a segmental ring 15 secured to the upper ends of said posts or standards 13, being preferably formed integral therewith, said segmental ring being cut away at one side in line with the elbow 5, as shown at 16, to form an opening of proper size to receive said elbow.

50 55 As shown, the posts or standards 13 are formed integral with the plate 14, which is clamped to the diaphragm by means of a stud 17 formed thereon, which extends through holes formed in said diaphragm and also in a plate 18 applied to the lower side of said diaphragm, and a nut 19 threaded to the projecting lower end of said stud.

60 65 For convenience in turning the clapper 7 to effect engagement and disengagement thereof with and from the opening 16 in the segmental ring 15, means are provided for

engaging a wrench with the side thereof which is exposed when the plug 11 is removed. As shown, said means consists of a flat-sided, specifically square, projection 20 on said clapper.

70 In practice, the accelerator valve will be installed with the diaphragm a² substantially horizontal and the casing section a uppermost. With this construction, it is obvious that the weight of the valve A¹ and of the plates 14 and 18 will exert a force on the diaphragm a², corresponding to an unbalanced air pressure in the compartment 1, tending to flex said diaphragm in a direction to close the valve A¹.

In accordance with my invention, the compartments 1 and 2 of the casing A are connected by a passageway which is of such small size that balancing of a differential air pressure in said compartments will occur gradually. Thus, when the accelerator valve is installed for use and the sprinkler system and thus the compartment 1 of the casing A are filled with air under pressure, it will require an appreciable interval of time for sufficient air to pass through the passageway from the compartment 1 into the compartment 2 to balance the air pressure therein, during which time the unbalanced air pressure in the compartment 1, acting on the diaphragm a² will operate to close the valve A¹, thus preventing

95 escape of air from the compartment 1 through the discharge opening 4 of said compartment. The weight of the valve A¹ and parts associated therewith, including the supporting posts or standards 13, the plates 14 and 18 100 and the nut 19 will maintain said valve A¹ closed, but, when the sprinkler system and thus the compartment 1 of the casing A are vented, an unbalanced air pressure will be produced in the compartment 2 which will 105 exert a force on the diaphragm a² tending to flex the same to open the valve A¹, opening of said valve occurring whenever the pressure in the compartment 2 is sufficient to flex said diaphragm against the force exerted thereon 110 by air pressure in the compartment 1 and the weight of the valve A¹ and associated parts.

115 My invention also comprises means for preventing said passageway from becoming clogged or closed by the lodgement therein of solid particles which are sufficiently small and light to be entrained by the air current passing through said passageway.

120 In the preferable construction shown, see particularly Fig. 3, the passageway connecting the compartments 1 and 2, designated 21, is formed in a plate 22, secured between the ends of tubular members 23 and 24 which are rigidly connected in any suitable manner, simple means for this purpose consisting of 125 screws which rigidly connect flanges formed on the connected ends of said tubular members. Tight joints are formed between said plate 22 and the ends of the tubular members by packing gaskets 25, said gaskets being pro- 130

vided with holes of substantially the same size as the inside diameter of said tubular members.

The remote ends of the tubular members 23 and 24 are closed by heads 26 and 27 which, as shown, are formed integral about the body portions of said tubular members. Said tubular members 23 and 24 thus form compartments 28 and 29.

Free access of air to and from said compartments 28 and 29 is provided for by means of open ended tubes 30 and 31 secured in holes formed in the heads 26 and 27 of the compartments 28 and 29, respectively.

Light, solid particles entrained by currents of air entering the tubes 30 and 31 are to a large extent separated therefrom by screens or strainers 32 and 33 of very fine mesh, say 100 mesh or finer to the inch, which surround entirely and enclose the projecting ends of the tubes 30 and 31. Preferably, also, the ends of said tubes are bent over so that their open outer ends will extend into close proximity to the heads 26 and 27, as shown at 34 and 35.

As a further precaution against clogging of the passageway 21 by lodgement of solid particles of matter therein, conical baffles 36 and 37 are supported within the compartments 28 and 29, respectively, the apexes of which are disposed inwardly towards the plate 22, and the remote sides of which form conical receptacles 38 and 39 adapted to receive any solid particles which may enter the compartments 28 and 29 thru the tubes 30 and 31, respectively.

As shown, the baffles 36 and 37 are supported between interior shoulders 40 and 41 formed on the tubular members 23 and 24 adjacent to their remote ends, and relatively small tubular struts 42 and 43 inserted between the apexes of said baffles and the plate 22. As shown, the remote ends of said struts are compressed so as to close the open ends thereof and are rounded, said rounded ends engaging corresponding recesses formed at the apexes of said baffles, all as shown at 44 and 45. The proximate ends of the struts 42 and 43 bear against the plate 22 and are confined in position thereon with their hollow interiors in communication with the passageway 21 by means of recesses formed in opposite sides of the plate 22 into which the ends of said struts are inserted. As shown, said recesses are formed in collars 46 and 47 secured to opposite sides of the plate 22.

Each of the baffles 36 and 37 is provided with holes or openings 48 arranged eccentrically to its axis and formed in each of the hollow struts 42 and 43 are holes 49 which connect the interiors of said struts with the compartments 28 and 29 in the tubular members 23 and 24, respectively.

The separator just described, designated as a whole B is adapted to be secured in a hole formed thru the wall of the lower cas-

ing section a^1 with the tube 30 disposed inwardly and in communication with the lower compartment 2 of the valve casing A, and the tube 31 disposed outwardly and in communication with a chamber 50 formed by recesses 51 and 52 in the wall of the chamber 2 and in a plug 53 threaded into the outer end of said recess 51.

Said chamber 50 is in open communication with the upper compartment 1 of the valve casing A defined by the upper casing section a by means of passageways 54 and 55 formed in the walls of the upper and lower casing sections a , a^1 , the proximate ends of which, respectively, are in open communication with small cavities 56 and 57 formed in the walls of said casing sections and opposite ends of a stud 58 rigidly secured in the wall of the lower casing section a^1 , and the projecting end of which engages a hole formed in the diaphragm a^2 and in the wall of the upper casing section a , said cavities being connected by means of a passageway 59 formed lengthwise thru the stud 58. Said stud 58 will operate in an obvious manner to insure communication of the passageways 54 and 55 when the valve casing A is assembled, and will also act as a dowel pin adapted to insure that the different parts of the valve will be assembled in proper, designed position relative to each other.

As shown, the separator B is removably secured in position by screw-threaded engagement of the tubular member 23 with the hole or opening formed in the wall of the lower casing section a^1 to receive it.

A particular advantage in mounting the separator B unit in the position and in the manner shown is that it may be quickly and conveniently removed for purposes of inspection, cleaning or repairs and again replaced.

To provide for turning the plug 53 to remove and replace the same, said plug is preferably provided at its outer end with a raised square or hexagonal portion 60 adapted to receive a wrench; and to provide for turning the separator unit B to remove and replace the same, the outer tubular member 24 is preferably provided with a square or hexagonal portion 61 which may conveniently be engaged by a wrench.

In the preferable construction shown, also, the screens or strainers 32 and 33 are secured to rings 62 and 63 fitted to reduced end portions 64 and 65 at the remote ends of the tubular members 23 and 24 and which are adapted to be secured in engagement therewith by means of set screws.

I claim:

1. An accelerator valve for venting an automatic sprinkler system, comprising a casing, a flexible diaphragm which divides the interior of said casing into separate first and second compartments which communicate with each other by means of a restricted

passageway, said first compartment being provided with an admission opening adapted to be connected with the sprinkler system, a hollow elbow on the valve casing which extends into said first compartment providing a discharge opening therefrom, a valve which controls said discharge opening comprising a clapper supported on the diaphragm of the accelerator valve, a valve seat formed on the inner end of said elbow, and means for guiding said clapper in its movement towards and from the valve seat, the means for supporting said valve clapper comprising a plate secured to the diaphragm of the accelerator valve and a post or posts on said plate to the upper end or ends of which said valve clapper is removably secured, the relation being such that the weight of the parts carried by the diaphragm of the accelerator valve forms the sole mechanical means for maintaining the valve clapper closed when the pressure in the compartments of the casing of said accelerator valve is substantially balanced, excess pressure in the first compartment

ment tending to close said valve and excess pressure in the second chamber forming the sole means for opening said valve.

2. An accelerator valve as specified in claim 1, which also comprises a segmental ring secured to the upper end of said post or posts in which the valve clapper is removably secured, the open side of said ring being in line with and proportioned to permit the passage therethrough of the elbow on which the valve seat is formed.

3. An accelerator valve as specified in claim 1, which also comprises a segmental ring secured to the upper end of said post or posts with which the valve clapper has screw-threaded engagement, the open side of said ring being in line with and proportioned to permit the passage therethrough of the elbow on which the valve seat is formed.

In witness that I claim the foregoing as my invention, I affix my signature this 1st day of August, A. D. 1924.

AL FRYER.
